UNITED STATES PATENT OFFICE.

HUGH J. RILEY, OF FORT SHAFTER, HONOLULU, TERRITORY OF HAWAII.

DESIGN FOR A TABLE.

44,710.

Specification for Design.

Patented Sept. 30, 1913.

Application filed July 23, 1913. Serial No. 780,796. Term of patent 7 years.

To all whom it may concern:

Be it known that I, HUGH J. RILEY, a citizen of the United States, residing at Fort Shafter, Honolulu, Territory of Hawaii, have invented a new, original, and ornamental Design for Tables, of which the following is a specification, reference being had to the accompanying drawing, forming a part thereof.

Figure 1 is a side elevation of a table

showing my design, Fig. 2 is a top plan view of the same, and, Fig. 3 is a bottom plan view.

I claim:

The ornamental design for a table, as shown.

HUGH J. RILEY.

Witnesses:

F. H. KIEFER,
P. H. BURNETTE.
